UNITED STATES PATENT OFFICE

JOHN RECKER, OF NEWARK, NEW JERSEY

KEYLESS LOCK

Application filed January 23, 1928. Serial No. 248,594.

This invention relates to locks of the keyless or dial actuated type and more particularly to such as are designed for use in securing bag frames when closed.

5 This type of lock has a very decided advantage for travelers, in that no key being required to control the lock, there is nothing to be lost, mislaid or carried about.

Furthermore, a dial lock is less liable to 10 yield by attempts at "picking" or other unauthorized means and resists opening to such as are unfamiliar with the combination.

It is therefore an object of the invention to provide a keyless lock having a plurality 15 of manually settable dials, all of which require placing in a predetermined position before the locking mechanism is released, but permits closing of the bag frame sides at any time irrespective of the position of the dials.

20 A further feature is in the provision of a lock of neat appearance, well suited for its purpose, and which contains relatively few and simple parts, all of which are capable of being cheaply constructed of sheet metal.

25 These and other advantages, which will become apparent as the description progresses, are attained by the novel construction, combination and arrangement of elements, hereinafter described and shown in the accompanying drawing, forming a material part 30 of this disclosure, and in which:

Figure 1 is a fragmentary top plan view 25 of a conventional bag showing an embodiment of the lock as applied to the side frames.

Figure 2 is a front view of the main portion of the lock, the catches being in section.

Figure 3 is a longitudinal sectional view taken on line 3-3 of Figure 1.

Figure 4 is a similar sectional view taken 40 in a plane at a right angle to Figure 3, on line 4-4 thereof.

Figure 5 is another sectional view taken on line 5-5 of Figure 3.

Figure 6 is a sectional view taken on line 45 6-6 of Figure 3, but looking in an opposite direction.

Figure 7 is a side elevational view of the keeper slide.

Figure 8 is a group perspective view of the 50 operative parts of the lock.

In the drawing, the numeral 10 designates one element of a bag frame of angular cross-section, the same having a flexible lining 11 and covering 12, through which are openings to receive the lock securing means.

55 The lock parts consist of a pair of catch elements 14 secured to one of the frame sides in any suitable manner, these catches having lateral recesses 15 and angular contact ends 16, as seen in Figure 1, being of the usual type of construction.

The lock casing 17, applied to the mating frame member, is preferably a hollow elongated rectangle, having semi-circular ends 60 and raised to project slightly above the frame members.

65 Extending at right angles from the ends of the casing are flattened prongs 18 adapted to pass through the openings in the bag frame and also other parts of the structure, as will later become apparent, whereby the same are rigidly held to the frame.

70 Disposed within the casing, to slide freely against its upper wall, is a flat plate 19 having rounded ends and containing a slot 20 at its center and equally spaced therefrom are other similar slots 20^a and 20^b.

75 Extending into the slots 20^a and 20^b, from one end, are tongues 21 and 21^a integral with the plate, and reaching down from the plate, on the same side, adjacent the slot 20, is a rigid lug 32.

80 Movable fitted to the central slot 20 is a circular disc 22, in which is fixed a post 23 extending through a slot 24 in the casing wall 85 and rigidly carrying a dial knob 25 by which the disc may be rotated and moved within the limit of the slot 20.

85 Other discs 26 and 26^a are disposed in the slots 20^a and 20^b, these discs having a notch 27 and 27^a in their respective peripheries, the same being engageable by the tongues 21 and 21^a, as best seen in Figure 4.

90 Axial posts 28 and 28^a, fixed in these discs, are rotatable in the casing wall but are not laterally movable, these posts rigidly carrying dial knobs 29 and 29^a, by which their respective discs may be rotated, these discs being of the nature of wards in a common lock.

95 The several discs and plate 19 are uniform 100

in thickness and have immediately below them a bottom plate 30 tightly fitted in the casing, the plate having an opening 31, through which the lug 32 extends to move limitedly endwise of the casing.

5 Adjacently below the plate 30 is a pressed metal box-like casing 42 having flat extended ends 33 containing openings 34, through which the prongs 18 pass, thereafter being 10 bent to clamp the structure rigidly on the frame side, as best seen in Figure 2.

Opposed pairs of lugs 35 are bent inwardly towards each other from the edges of the casing 42 and on which is movably seated a 15 channel shaped slide 36, the same having an opening 37 to receive the end of the lug 32, by which motion may be transmitted to it.

The slide or keeper 36 is provided in its front wall with spaced apart openings 37 to 20 permit the entrance of the catches 14, the same also passing through openings 38 in the front wall of the casing 42.

A tension spring 39, attached at its ends 25 respectively to the casing 42 and keeper slide 36 by a pin 40 maintains the lock in a normally closed position, but permits the slide to move against the spring when the catch elements 16 are forcibly presented in the openings 37, and also when the central knob 25 is manually actuated to move the slide by reason of the plate 19 and its lug 32.

The several discs are corrugated near their 30 tops to aid in manipulation and are provided with numerals on their faces to register with a line 41 on the top of the casing.

As has been seen, the sides of the bag may be closed at any time without respect to the position of the dials, causing a locking effect between the keeper slide 36 and catches 14.

40 When it is desired to unlock the bag, the knobs 29 and 29^a on the outer casing must be positioned to bring the disc notches 27—27^a into register with the lugs 21—21^a, permitting the central knob 20 to be moved and 45 carry with it the plate 19 and keeper slide 36 in the inner casing, thus freeing the catches to permit their withdrawal, the spring 39 returning the several parts to their normal engaging position when the pressure is released.

Obviously the plate 19 and lugs 21—21^a prevent moving the knob 25 whenever the discs 26—26^a are rotated into other than a position to receive the lugs, thereby constituting 55 an essentially safe and simple form of lock.

Although the preferred embodiment of this invention has been explained in detail, it is to be understood that changes therein may be made without conflicting with the 60 scope of the appended claims.

Having thus described my invention, what I claim as new and desire to secure by Letters Patent, is:—

65 1. A keyless bag lock comprising a casing having two sections, one being fixed on the

outer side and the other to the inner side of one of the bag frame sides, a catch carried by the mating frame side to enter the inner section, a spring actuated slide to normally retain the catch in said section, a plate slideable in the outer section directly connected with said slide to communicate motion thereto, means on the outer section to actuate said plate, and a pair of independently operable means when set in a predetermined position permitting movement of said plate and when in any other position preventing movement thereof.

2. A keyless lock comprising a casing, a catch enterable therein, a slide engageable with said catch, said slide being spring impelled, a plate slideable in the casing, said plate having three elongated openings, tongues on said plate extending into two of the openings, a lug on said plate engaged in said keeper, discs rotatable in the openings, two of said discs having notches to receive said tongues when in register therewith, the third disc having a plain periphery, knobs carried by said discs operable on said casing, and means on said knobs to indicate the position of the notches in the discs, said third knob being slideable longitudinally of the casing whereby said plate and slide may be actuated to release the catch when the two discs are in position to receive the tongues.

3. A keyless lock comprising a casing, a catch enterable therein, a slide engageable with said catch, said slide being spring impelled, a plate slideable in the casing, said plate having three elongated openings, tongues on said plate extending into two of the openings, a lug on said plate adapted to engage said keeper, discs rotatable in the openings, two of said discs having notches to receive said tongues when in register therewith, the third disc having a plain periphery, knobs carried by said discs operable on said casing, a plate immediately below the first named plate, said plate having an aperture through which the lug extends, and means on said knobs to indicate the position of the knobs in the disc said third knob being slideable longitudinally of the casing to actuate the plate and slide to release the catch when the other two discs are in position to receive the tongues.

This specification signed and witnessed this fifth day of January, 1928.

JOHN RECKER.
